21 Claims. (Cl. 62—19)

1

This invention relates to an improved convertible ice bunker for use in refrigerated vehicles. Although the invention will be described and illustrated with particular reference to its use in refrigerated railroad cars, we do not intend this fact or the detailed structure shown to be interpreted as limiting the scope of our invention.

By a convertible bunker we mean one in which the bulkhead between the ice compartment and the cargo compartment of the car is movable and can be stowed, against the end wall of the car or elsewhere, so that when refrigeration is not required the bunker space can be made available for cargo. Such a convertible bunker is shown for example in Patent No. 2,324,749 issued on July 20, 1943. General purposes of the present invention are to provide an improved convertible bunker which is more convenient in operation, relatively light in weight and yet sufficiently strong to be satisfactorily durable, and which is still relatively economical to produce and simple to install.

Other objectives of the invention are to provide a bulkhead which can be moved from its bunker forming position to its lading position quickly and easily by one man, and which can be strongly and securely locked in each position without requiring the manipulation of any special locking mechanism. In addition we provide for convenient rearrangement of the ice supporting grate structures between their normal icing position, their upper position for stage icing, and their lading position in which they form a continuation of the floor of the car for loading cargo.

A further and important object of the invention is to provide mechanisms by which the bulkhead may be moved from its bunker forming position not only to a lading position against the end wall of the car but also toward the center of the car in such a manner as to make the bunker space readily accessible from the interior of the car, even while the grate sections are in their normal or in their lading position. The possibility of this motion is valuable, particularly when it can be obtained with the same convenience as the motion to and from the lading position, because it avoids the necessity of removing old ice from the bunker through the hatches.

Moreover, the invention takes account of human fallibility by providing features in the operating mechanism of the bulkhead which make for safety and tend to insure correct and complete operation.

Other objectives and advantages of the invention will be clearly understood from the following

full description of an illustrative preferred embodiment. It will be understood that details of this particular embodiment are subject to wide variation within the scope of the invention, and are not to be construed as a limitation of that scope. In describing this embodiment we refer to the attached drawings, of which:

Fig. 1 is a partially cut away plan view of the complete installation for one car end;

10 Fig. 1a (see sheet eight of drawings) is an enlarged view showing the upper left hand portion of Fig. 1;

Fig. 2 is a vertical section taken parallel to the longitudinal car axis on line 2—2 of Fig. 1;

15 Fig. 2a (see sheet three of drawings) is a fragmentary enlargement of certain portions of Fig. 2;

Fig. 3 is a vertical transverse partial section taken on line 3—3 of Fig. 2 with the ice grates removed, showing in elevation the grate-supporting frame structure as installed against the end wall of the car;

20 Fig. 4 is a partially cut away fragmentary elevation of the convertible bulkhead in its bunker forming position;

25 Fig. 5 is an enlarged partially cut away elevation of the upper central part of the bulkhead, including the bulkhead lifting mechanism, and showing the supporting track in transverse section;

Fig. 6 is a vertical transverse section through the central column of the bulkhead, taken on line 6—6 of Fig. 5, showing the bulkhead lifting mechanism in its bulkhead locking position;

Fig. 7 is a section similar to Fig. 6, but showing the bulkhead in its raised or free position;

Fig. 8 is a partially cut away plan view of the central upper part only of the bulkhead, omitting the lifting mechanism;

Fig. 9 is a schematic plan view of the car interior, indicating for one preferred type of track installation the positions assumed by the bulkhead for bunker formation, for lading, and for giving access to the bunker space;

45 Fig. 10 is a plan view similar to Fig. 9 for a second preferred type of track installation showing two alternative ways of moving the bulkhead; and

Fig. 11 (see sheet three of drawings) is a fragmentary section taken on line 11—11 of Fig. 4, showing bulkhead locking means installed on the car wall.

Referring first to Figs. 9 and 10, the car walls are indicated at 15 and the convertible bulkhead is shown schematically in its bunker forming po-

sition *a*, in which it is releasably locked by restraints, indicated at 16. To move the bulkhead, it is lifted by operation of lever 160, and suspended from a trolley on track 80 which is secured to the ceiling structure of the car. As will be explained below, the process of lifting the bulkhead automatically releases it from restraints 16, permitting it to be rolled freely along track 80 in either direction, and also to be swiveled about the vertical hanger rod by which it is suspended from the trolley. Thus the bulkhead can readily be moved inward to the lading position *b* against the end wall of the car, where it is lowered and automatically locked in position by restraints indicated at 16a. When the bulkhead is lowered in either of its two operating positions *a* and *b*, lever 160 is latched in its folded position within the bulkhead, and this automatically locks the bulkhead in engagement with the restraining means 16 or 16a.

With the bulkhead in position *b* the bunker space is available for cargo, and vertical air passages through the body of the bulkhead provide an air circulation path similar to that through the bunker space when the bulkhead is in position *a*. As will be explained below, the floor structure is such as to cut off this vertical circulation path through the bulkhead in position *a*, but to leave it open in position *b*.

The bulkhead is similarly movable on its trolley outward from the car end wall. In the preferred embodiment shown in Fig. 9, track 80 is straight, and the bulkhead can be moved to the inner end of the track and swiveled on its support into position *c*. This gives access to the bunker space from the interior of the car, permitting easy shifting of the ice grate sections from one position to another (see below) and allowing old ice to be readily removed and the bunker space cleaned. In position *c* the bulkhead can be left suspended from its trolley, or it can be lowered until its lower edge rests on the cargo floor, lever 160 being returned to its folded position within the bulkhead.

An alternative form of overhead track is shown schematically in Fig. 10. Section 80b of this track, outward from the car end wall beyond bunker forming position *a* of the bulkhead, is curved toward the car side wall. With this general form of track the bulkhead can be swiveled in either of two ways as it is drawn outward from position *a* to give access to the bunker. As indicated in the lefthand portion of Fig. 10, the bulkhead can be swiveled counterclockwise through position *d* into position *e* with its normally inner face directly against the car side wall. Or the bulkhead can be swiveled clockwise, as indicated in the righthand portion of Fig. 10, pivoting about one end, which may be provided with a stop or hinge shown schematically at 18. This motion brings the bulkhead to a diagonal position such as *f*, lever 160 preventing it from folding flat against the car side wall.

In describing the structural details of the complete illustrative installation contemplated by the invention, we will consider first those parts of the structure which are rigidly installed in the car, or which are closely associated with such rigid parts. These comprise principally, first, the horizontal base or floor frame, shown partially in plan in the lower part of Fig. 1; second, the vertical end wall frame, seen in elevation in Fig. 3; and third, the bulkhead supporting track which extends from the end wall toward the center of the car along the center line of the ceiling.

The horizontal floor frame is a rectangular grid structure underlying both the bunker itself and the bunker forming bulkhead, and comprising the bulkhead supporting girder 20 of shallow inverted channel section (see Fig. 2a) which runs transversely substantially the entire width of the car interior; the longitudinal spacing members 21 of channel section (see Figs. 3 and 4) which support base girder 20 and are joined together at their outer ends by it; and the connecting cross member 22 which joins and supports the inner ends of members 21 (through spacing blocks 24), and which runs essentially the entire width of the car at its end. The members 20, 21 and 22 are welded together, forming a rigid base frame the inner side of which is bolted to the end of the car by the bolts 23, and the outer end of which is bolted by means of bolts 27a (see Fig. 2a) to the transverse floor beam 27 of the car, a wood filler 27b being interposed to provide good support for the base frame. Members 21 at their outer ends are of such vertical dimension as to support the flat upper surface of base girder 20 in the horizontal plane of the lading floor of the refrigerator car, one removable section of which is indicated at 46 in Fig. 2. Members 21 are of general U-form, as is shown in Figs. 3 and 4, a section of the upper bent flange of the U being left straight at 21a, and extending vertically within and welded to base girder 20, as shown in Figs. 2a and 4, effectively anchoring this girder against transverse motion and supporting its load carrying surface. Members 21 taper in their vertical dimension inwardly toward the end of the car, the form of their section in the immediate neighborhood of cross member 22 being shown clearly in Fig. 3.

The tapered form of members 21 accommodates the movable ice supporting grate sections 39 when these are placed in the lading position A, illustrated in Fig. 2 by the solid lines. These grate sections are approximately the same size as, and are equal in number to, the rectangular openings in the horizontal base frame, as may be seen from Fig. 1. They are composed of tapered longitudinal beams 31 of sheet metal and cross slats 32 (see Fig. 2a), both set on edge to give greater load supporting strength and also to allow free vertical circulation of air through the grate. The tapered outer end of each grate section (the end adjacent the bulkhead) is strengthened by the channel cross member 33, welded to beams 31, and through which the load carrying contact is made with the various types of brackets provided for this end of the grate. The inner and thicker end of each grate section, which is toward the end of the car, is similarly strengthened by cross member 34 which crosses and is welded to the ends of beams 31 where they are cut off at a slant (Fig. 2a), this shape facilitating handling of the grate, as will be more fully appreciated presently. The slanted ends of all the beams 31 of each grate section are uniformly slotted at 35, providing a channel for transverse rod 36, which is retained therein by cross member 34. The function of the rod 36 is to prevent the grate section from being removed from the car, while yet allowing it to be shifted from one position to another, as will be explained. The lower edges of beams 31 are also notched at 37 close to their thicker inner ends, forming a groove formation which fits over the lower flanges of horizontal grate supporting channels 61, 62 and 63 of the wall frame (see below). Two grooves 38 and 39 in the upper surface of the grate sections are

similarly formed parallel to the inner edge of the grate by the series of notches 38 and 39 in beams 31. These accommodate the lower edges of the bulkhead when it is stowed against the end wall of the car in the position indicated by the dash-dot lines in Figs. 2 and 2a.

A sheet metal drip pan 40, shown in section in Figs. 2 and 2a, is set below the floor frame, extending the full car width, and supported by the transverse floor supporting members 21 and 23 of the car. Conventional drains, indicated schematically at 41, are provided to carry off water and debris from the pan. At the end of the car, pan 40 extends under and behind cross member 22 of the floor frame, connecting with the sheet metal lining of the end wall of the car (see below). Inward toward the center of the car, pan 40 laps under the regular water-tight covering 44 of the permanent car floor.

Section 46 of the lading floor can conveniently be hinged to brackets 43 which are bolted to two or more of the members 21 of the floor frame. The very simple form of hinge indicated at 44 consists of a circular notched hole in bracket 43 and two horizontally adjacent pins in the floor section. The pins are normally retained in the hole, but when the floor section is raised to a vertical position they can be lifted out through the notch.

The above described preferred construction of the horizontal floor frame is well adapted for permitting free access of air to the lower part of the bunker space. Air can be circulated between the permanent car floor 44 and lading floor 46 by a centrifugal fan of the type described in the Van Dorn Patent No. 2,349,315, issued on May 23, 1944. Such a fan, indicated schematically at 42 in Fig. 2, draws air down through the slatted lading floor in the central part of the car and draws and drives it toward the end of the car between the two floors. Our manner of supporting base girder 20 and the bulkhead above it causes little or no interference with the free flow of this air into the lower part of the bunker. This is clearly shown in Fig. 4, the spaces below girder 20 and between members 21 being entirely open.

The frame 50, which supports the outer ends of ice grate sections 30 in their intermediate icing positions (B in Figs. 2 and 2a), is composed of struts 51 of inverted U-section welded at their inner or upper ends to the cross member 52 to form a single rigid unit (see Figs. 1, 2a). The free outer or lower end of each strut is pivoted at 53 to one of the members 21 of the floor frame, so that frame 50 can be lifted from the folded position shown in solid lines in Fig. 2a to the vertical grate supporting position shown in dashed lines. In the folded position the inverted U-shaped struts 51 fit over the upper edges of base members 21. Cross member 52, which is of angle section, is notched to fit over members 21. In the folded position frame 50 thus extends above base members 21 only by the thickness of the webs of channels 51 and angle 52. Struts 51 are notched at their outer pivoted ends, to cut away their upper webs and the upper edges of their side flanges at 54, to facilitate their upper raised positions, and particularly to clear the inner edge of the apron 20a which projects inwardly from the lower edge of the inner flange 20b of channel girder 20 (Fig. 2a). In the upper position, the corner of each notch 54 in struts 51 overhangs and rests on apron 20a so as to take the load thrust off pivots 53.

The narrow apron 20a extends transversely over base members 21 and forms a supporting apron for the outer edge channels 33 of the grate sections in their lowest positions A. With 5 33 thus supported the lower edges of grate beams 31 are above the frame 50 in its folded position and will not contact that frame; even if the grate sections are somewhat laterally displaced. It will be noted from Fig. 1 however that the width 10 dimension of each grate section, and the spacings of the sections (maintained by the end wall framing as described later) are such that the grate sections do not normally directly overlie the members 21 or the struts 51.

The second principal fixed element of the car installation is the end wall frame, shown in partial horizontal section in Figs. 1 and 1a, in vertical section in Figs. 2 and 2a, and in partial elevation in Fig. 3. The principal function of the 20 wall frame is to support the inner ends of the ice grate sections 30 at each of their three alternate levels. This rigid wall frame is composed of the shallow vertical channel members 60 (and 60a) joined at their lower ends by the equally 25 shallow horizontal channel 61, at an intermediate level by the similar channel 62 and at the top by the channel 63. The outermost vertical channels 60a, next the car side walls, need be only half channels, as will become obvious. Only upper horizontal channel 63 is continuous across the car; lower channels 61 and 62 being broken by the continuous vertical channels 60; as is shown clearly in Fig. 3. At various of the 30 corners of this rigid frame, and preferably flush 35 with its back surface, gusset plates 64 are welded in place. The wall frame is secured in the car against its end wall structure by bolts 65 seated in gusset plates 64 or in upper channel 63. The weight of the frame and of whatever load it carries is supported from below, its lower edge resting directly upon the upper horizontal flange 40 surface of cross member 22 of the horizontal floor frame. As shown best in Fig. 2a, this cross member is of Z-section with its upper flange supported 45 on a part of the car framing.

The edges of the lower flanges 66 of horizontal channels 61, 62 and 63 are bent upward (Figs. 2 and 2a) to form flange lips 66a over which the grooves 37 in the lower surfaces of grate sections 30 (see above) are adapted to be hooked. The lips 66a do not themselves support the grate sections, the ends of which rest upon the relatively wide horizontal surfaces of flanges 66 within the channels; but they retain the ends of the grates 55 within the channels. Thus the inner ends of the 50 grate sections are supported directly by the wall frame in all three of their alternative positions, channel 61 being at the correct level for the lowest position A of the grates (solid lines in Fig. 2); channel 62 for the intermediate position B (dashed lines in Fig. 2); and channel 63 for the stage icing position C (dot and dash lines in Fig. 2). In these 60 three positions the outer ends of the grate sections are supported respectively directly by apron 20a of channel 20 of the base frame; by frame 50, described above; and by brackets 114 welded 65 to the inner face of the bulkhead.

The form of vertical channels 60 is adapted to 70 interlock with and retain the hooked ends of retaining rods 36, mounted on grate sections 30 as described above. (See Fig. 1, the extreme left portion of which represents a section through the end frame taken on line 1'-1' in Fig. 2a; except that below the point of Fig. 1 indicated by 75 "g" the section is taken on line 1"---1" of Fig. 2a.

See also the enlargements in Figs. 1a and 2a where the nature of retaining rods 36 is more clearly shown.) This interlocking of retaining rods 36 with vertical channels 60 provides a connection between the grate sections and the wall frame which prevents easy removal of the grates from the car, yet allows easy manipulation of the grate sections to move them from one position to another. As shown best in Figs. 1a and 2a, each end of each retaining rod 36 is provided with a hook formation which is made up of a transverse part 36a and a reentrant hook end 36b which hooks into the channel 60 (or 60a) behind the front edge lip 60c of the channel flange 60b. Each rod 36 thus has hooks at both its opposite ends which hook in opposite directions behind lipped flanges of adjacent vertical channels 60 and/or 60a, so that the rods cannot be removed from the channels without deformation.

The transverse hook parts 36a are of some length, longer than they appear to be in Figs. 1 and 1a. With a grate section hooked into a horizontal channel for support (see e. g. Fig. 2a) the transverse hook portions 36a extend either upwardly or downwardly to hook their ends 36b into the vertical channels. When the end of a grate section is lifted out of a horizontal channel, the lengths of hook portions 36b allow the section to be moved outwardly far enough to clear its inner end from the channels. The section can then be moved up or down the end wall frame to be hooked into any other horizontal channel as desired. The lengths of the slotted notches 35 in which rods 36 are confined (their lengths as seen in Fig. 2a in a direction lengthwise of the grate beams 31) also perform the same offices as the lengths of transverse hook portions 36a. In either case, whether it is the lengths of 36a or of notches 35 that allow freedom for movement, the rod hooks 36b remain interlocked with the channels 60, sliding up or down in them.

To move one of the grate units while the bulkhead is still in its bunker forming position (Fig. 2), the outer end (the bulkhead abutting end) of the grate section is first lifted six or eight inches, the grate pivoting about its inner end which rests in one of the channels 61, 62 or 63. The slanting position of end member 34 of the grate section allows this tilting movement. The inner end is then lifted enough to disengage its groove 37 from the lower flange of the channel (groove 38 helping to avoid interference with the upper flange of the channel). The entire grate section can then be moved toward the bulkhead far enough to disengage its inner end completely from the channel. It can then be moved up or down to another position, its inner end being inserted into the selected channel while its outer end is relatively elevated, thus reversing the procedure just described. The outer end is firmly lowered onto the selected support.

If the grate sections are being moved between positions A and B it is necessary to raise or lower frame 50. This operation is greatly facilitated by the fact that the bulkhead can be moved out from the bunker space, for example to position c in Fig. 9 or to position e or f in Fig. 10. When shifting frame 50 it is convenient to stack all the grate sections temporarily against the end wall of the car in a nearly vertical position, their inner ends (which are linked to the car end wall) elevated and their outer ends resting on members 21 of the horizontal floor frame inward of frame 50. In this position, the grates do not interfere with access to or rotation of frame 50 about its pivots

53. During all these operations the inner ends of the grates are held close to the wall frame by retaining rods 36, which do not, however, prevent the motions described.

Before the wall frame is bolted in place in the car the end wall of the car may be rendered water-tight by a plain sheet metal sheathing covering the entire wall and with its lower edge lapping inside the vertical rim of water pan 40. However, an appreciable increase in the thickness of insulation in the end wall of the car can be obtained by constructing this sheathing of formed, interiorly recessed, panels, fitting the various rectangular apertures of the wall frame itself, and permanently welded thereto to form a watertight structure. Such panels are shown in section in Fig. 2 at 70 and 71. By their use essentially the entire volume between the front and back faces of the wall frame is made available for insulation. If this additional insulating volume is not required, as would normally be the case in cars newly constructed, the simpler procedure mentioned above is to be preferred.

The horizontal overhead track 80 is preferably formed of a single piece of approximately square inverted U-section, with in-turned flange edges, shown for example in Fig. 5. The flange edges of this channel are bent inward more than 90° at 81, providing two parallel rails. Track 80 is set into the ceiling of the car, shown in section at 82 in Fig. 5, approximately flush with its lower surface, and is supported in any suitable way by the structural framing of the car ceiling or roof, not shown. The track extends along the center line of the car from the car end wall past the normal bunker forming position of the bulkhead (Fig. 2), continuing toward the center of the car from this position a distance somewhat greater than one-half the interior width of the car. The latter part of the track may be straight as indicated schematically in Fig. 9, or it may depart from the center line of the car, for example along a curve as indicated schematically in Fig. 10.

It will be noted that the illustrated preferred sectional form of track 80 locates the rails 81 in a protected position within the channel. In addition, the rails are in accurate vertically spaced relation to the upper horizontal web surface 83 of channel 80. This surface forms a roof over the rails, performing the important function in our invention of locking the entire bulkhead against upward motion out of either of its operating positions a and b (Fig. 9). It may be desirable, as will be explained below, to cut away this horizontal roof section of channel 80 near the end of the track in the general region indicated at 84 in Fig. 2. A removable stop is preferably provided near the end of the track. This may take the very simple form of the horizontal bolt shown at 85 in Figs. 2 and 5.

The bulkhead supporting trolley 90 operates on four wheels 91, two running on each of the rails 81 within track 80. The wheels turn on conventional bearings on axles 92 which project transversely from trolley body 94. The latter may consist, for instance, of two axle supporting blocks welded to a central thicker block containing the vertical hole 93. This hole acts as a swivel bearing for bulkhead supporting hanger rod 155, the weight of the bulkhead being transmitted to the top surface of the central block of trolley 94 by the head 157a at the upper end of rod 155 (see below).

Preferred construction, according to the invention, of the movable bulkhead itself results in a

relatively light structure of adequate strength, well adapted to withstand the particular stresses to which it is subjected. The bulkhead is made up of the vertical central column 120 which accommodates the bulkhead lifting mechanism to be described below, and four preferably identical box units 100, two on either side of the central column. These five units, each of which extends essentially the full height of the bulkhead, are connected together only by two horizontal channel members 130 and 140 which form the upper and lower edges of the bulkhead, and to which the separate box units and central column are independently connected, preferably, for ease of assembly, by the bolts indicated at 110 and 110a (see Figs. 2 and 4). The lower connecting channel 130 is of inverted U-section (Figs. 2 and 2a), of such dimensions that, with the bulkhead in bunker forming position, it fits over and partially encloses the U-section of base girder 20 of the horizontal floor frame described above. The upper horizontal connecting channel 140 is in part of similar U-section, but includes a relatively wide horizontal reinforcing section 141 by which the rigidity of the channel against horizontal deformation is greatly increased without adding unduly to its weight.

The box units of the bulkhead structure are shown in transverse vertical section in Fig. 2, in vertical elevation and section in Fig. 4, and in partial horizontal section in Fig. 1. They are preferably made of sheet metal assembled entirely by welding and include an outer rectangular welded frame composed of vertical edge channel members 101 and horizontal top and bottom channel members 102, all with their flanges facing outwardly. The vertical edge channels are spaced and strengthened by the horizontal webs 103 which are pierced by the flanged holes 104 to permit vertical air circulation through the interiors of the box units. The frame thus formed is covered on both faces by corrugated sheet metal sheathings 105, which become the load supporting facings of the bulkhead. All four edges of webs 103 are flanged, providing at their ends vertical surfaces 106 adapted to be welded to vertical edge channels 101, and along their sides flanges 107 which may, but need not, be welded to the corrugated sheathings 105. The sheathings are welded at their upper and lower edges to upper and lower channels 102, and at their vertical edges to vertical frame channels 101.

Corrugated sheathings 105 on both faces of the bulkhead box units are pierced near the top by air passages 111 located between upper channel 102a and upper web 103a of the box frame. Openings 111 in the present preferred embodiment are of oval shape and are confined to the trough-like depressions of the corrugated sheathing (as seen from outside the bulkhead). This leaves the ridges of the corrugations with their stiffening properties essentially unimpaired. Further strength is obtained in the manner of construction of openings 111 themselves. In forming each opening two vertically spaced holes are made and connected by a vertical cut on the axis of the holes. The material on each side of this cut and on the periphery of both holes is then pressed inward, producing a single oval hole entirely surrounded by a strengthening flange of somewhat irregular contour. The vertical part of this flange is indicated at 112 and the circular part, surrounding the ends of the oval hole, at 113 in Figs. 1 and 2. Holes 111 in both faces of the bulkhead normally allow circulation of air

through the bulkhead between the upper part of the bunker and the main cargo section of the car; in addition, when the bunker is stowed against the end wall of the car, the openings in its front face cooperate with openings 104 in webs 103 and similar openings 131 in bottom channels 102 and 130 to provide a vertical circulation path through the interior of the bulkhead itself.

- 10 In each box unit the upper and lower ends of edge channels 101 are bent out at right angles to form horizontal surfaces in contact with horizontal upper and lower channels 102 near their ends. The double thickness of metal where vertical and horizontal channels of the box frame overlap provides a reinforced seat for connecting bolts 110, which join the box units to top and bottom connecting channels 140 and 130. Moreover, upper and lower channels 102 of each box unit are of such section (Fig. 2) that they fit closely over the U-section of horizontal connecting channels 130 at the base of the bulkhead and 140 along its top, providing a joint of great strength against transverse stresses, quite apart from connecting bolts 110.

Central vertical column 120 is basically a single piece of sheet metal formed into a box column of generally rectangular cross section but with most of the front wall omitted, as is shown clearly in Fig. 8. Horizontal web 123, shown in Figs. 5 and 6, extending between and welded to the two opposite side walls 125 of the column, prevents merchandise from spilling into the lower part of the column behind facing 139. The inwardly turned vertical flanges which are all that exist of the front wall of the column are indicated by the numeral 121. Angle brackets 122 are welded inside the side walls 125 of the column at its extreme top and bottom, and abut against the horizontal surfaces of connecting channels 130 and 140. Bolts 110a connect these angle pieces to the channels, rigidly joining the vertical column to the rest of the bulkhead structure.

The front surface of nearly the entire bulkhead may be covered if desired by a smooth apron of wood or other appropriate material for thermal insulation and through which the thrust of the cargo will be transmitted to the bulkhead, reducing the possibility of damage both to the cargo and to the bulkhead. Such an apron is indicated at 139 in Figs. 1, 2, 2a and 4, but for clarity is omitted in other drawings where it might appear. A vertical slot, as indicated at 142 in Fig. 4, must be provided in the upper central part of the apron to allow operation of the bulkhead lifting mechanism (see below).

The clearance between the side edges of the bulkhead and the car walls may be filled in any suitable way, such as by the wood sealer strips indicated at 145 in Fig. 4, attached to the outermost box unit verticals 101. These sealer strips may have rounded outer contours which fit closely against the car wall and yet allow the bulkhead to be moved freely; or the space may be sealed completely against both air and water by use of rubber flaps or the like. However, we have found that with the construction shown even the wood fillers 145 may be omitted without endangering the cargo and without disturbing appreciably the intended path of circulation of air.

When it is desired to change the position of the bulkhead in the car for any of the purposes mentioned above, the entire bulkhead is lifted vertically a short distance and its weight supported entirely by trolley 90 on track 80. This lifting

operation automatically frees the bulkhead completely from the restraints which normally hold it in one of its two operating positions. An important feature of the invention is the manner of securing the bulkhead in place, which yet allows complete release when it has been lifted an inch or two.

When the bulkhead is in bunker forming position (Fig. 2) it is restrained along its entire lower edge against transverse motion (that is, against motion parallel to the length of the car). This restraint results from the interlocking along their entire lengths of lower connecting girder 130 of the bulkhead and horizontal base girder 20 of the floor frame. Since this interlocking between the lower edge of the bulkhead and the horizontal floor frame extends continuously across the car, not only is the weight of the bulkhead uniformly distributed and supported along its lower edge, but the transverse thrust, which may be very large, exerted on the bulkhead by the cargo, is also uniformly distributed to the floor frame and transmitted by it to the car framing. For this reason lower horizontal connecting channel 130 of the bulkhead does not need to be particularly heavy. Even base girder 20 of the floor frame, which supports the entire weight and thrust load, can be reasonably light, since it is supported at frequent intervals by members 21 which transfer both weight and thrust directly to structural members of the car frame. When the bulkhead is moved to its lading position against the car end wall, its lower edge is similarly restrained along its entire length by the flanges of lower channels 102 and 130 engaging notches 38 and 39 in the upper edges of grate beams 31.

On the other hand, the upper edge of the bulkhead is restrained in both these operating positions by stops which locate upper connecting channel 140 of the bulkhead only at its extreme ends. It is for this reason that upper channel 140 is provided with the strengthening flange 141 referred to above. Channel 140 extends at both ends beyond the edge of the outermost box unit of the bulkhead (Fig. 4), and overlaps the horizontal flanges of the angle irons 150 which are bolted to the side walls of the car close to the ceiling. Short sections of angle iron are welded to angle irons 150 at 151, 152 and 153 (Figs. 2 and 11), forming stops which restrain transverse motion of the bulkhead by confining horizontal connecting channel 140 near its ends where it overlaps angle flanges 150. Stops 151, which are strengthened by the supporting webs 151a, and stops 152 prevent inward and outward motion respectively of the bulkhead in its bunker forming position. Stops 153 hold the bulkhead against the end wall of the car when the bunker is converted into cargo space. Since these stops extend only a few inches above the lower horizontal flanges of irons 150, they restrain channel 140 only when the bulkhead is in its lowered position. When it is raised (see below) the ends of channel 140 are lifted clear of stops 151, 152 and 153, just as lower connecting girder 130 of the bulkhead is lifted clear of base girder 20 of the floor frame. Thus in its lifted position the bulkhead is free of restraint against movement toward or away from the end wall.

The upper stops just described could be individually located and supported on the side walls of the car, eliminating irons 150. However, the preferred method of supporting the stops, as shown in the drawings, simplifies their accurate

location in the car and provides a stronger mounting than would be available for them individually. It will be observed that thrust exerted by the cargo against the bulkhead, which is by far the largest force to be considered in such an installation, is transmitted from the upper corners of the bulkhead to irons 150 and from the lower edge of the bulkhead to members 21 of the horizontal frame, and is ultimately supported in both instances directly by the end structure of the car. As shown in Fig. 2, the ends of angle irons 150 abut the end wall structure.

The bulkhead lifting mechanism, which is contained as mentioned above within vertical central column 120 of the bulkhead itself, (see Figs. 5, 6 and 7) has the chief mechanical function of retracting or extending vertical hanger rod 155 which projects from hole 156 in upper connecting channel 140. Lever 160, shown as a solid steel rod of rectangular section, carries a handle 159 at one end and its other end is welded to the short shaft 161 from which it projects generally radially. Shaft 161 is journaled at one end directly in a hole in reinforcing plate 162 on one side wall 125 of column 120, and at the other end in collar 165 which rests in a similar but larger hole in reinforcing plate 163 on the opposite wall 125 of the column. Shaft 161 is restrained against axial movement by two cotter pins, 164 bearing against reinforcing plate 162 and 164a against collar 165. The collar in turn is restrained against endwise movement by rod 166 which is welded to it and which bears against plate 163.

Rod 166 is shaped as shown in Fig. 6, with a straight vertical section 168 in contact with the back wall 126 of column 120 and a hook 167 at its end which extends through opening 169 in the wall. This hook acts as a latch for the central ice grate section (see below) and neither it nor collar 165 plays any active part in the operation of the bulkhead lifting mechanism. The collar has the useful effect, however, of increasing the size of the bearing hole in plate 163, thus facilitating installation and removal of shaft 161 and lever 160. Collar 165 also serves as a convenient and strong means of anchoring rod 166 to the framework of the bulkhead. However, this rod with its hook 167 can instead be secured to the bulkhead structure in any other suitable way. The function of hook 167 is to engage under and behind cross member 33 of the central ice grate section when the grates are in their stage icing position C. This prevents the bulkhead from being moved accidentally toward the center of the car under those conditions. Even though the bulkhead has been raised and thus freed from other transverse restraints, it is linked to the grate section by hook 167, and the grate is linked to channel 63 of the wall frame, as described above. Thus the supporting bracket 114 cannot be pulled from under the outer ends of the grates, which would allow them to drop, spilling the ice and possibly damaging the equipment. To move the bulkhead, under those conditions, it is necessary to first move the grates from position C, after removal of any ice. That kind of operation, however, is only necessary with the grates in position C; with the grate sections in the more usual positions A or B, the bulkhead can be moved outwardly without the necessity of first moving the grates or any ice.

Returning now to the bulkhead lifting mechanism proper, the lower end of hanger rod 155 is threaded internally to receive rod 175, providing a

convenient length adjustment for the hanger rod. The lower end of rod 155 passes horizontally through the pivot lug 177 rigidly mounted on lever 160 near its supporting shaft 161. When lever 160 is pulled down from the position shown in Fig. 6 to that in Fig. 7, lug 177 is rotated in a vertical plane around shaft 161, acting on hanger rod 155 like a crank and retracting it a definite distance within the frame of the bulkhead. Since appreciable downward motion of hanger 155 relative to fixed track 80 is stopped by contact of its head 157a with the top of carriage block 94, this retraction of the hanger results in lifting the bulkhead and suspending it from carriage 90.

Head 157a can be constructed as an integral part of hanger rod 155, but the preferred construction shown most clearly in Fig. 6 greatly facilitates assembly and disassembly, particularly when trolley 90 is to be removed for overhaul. The hollow upper end of rod 155 encloses the shank of pin 157. This pin carries head 157a. The pin and rod are releasably locked together by clip 158, so that head 157a is effectively a part of rod 155. To remove trolley 90 from track 80, clip 158 is removed and rod 155 is lowered, by operating handle 159 or if necessary by disassembling the rod from bearing 177, until pin 157 is released. Removal of track end stop 85 then permits the trolley to be run off the end of the track without disturbing the bulkhead itself.

A locking brace in the form of a short section of channel iron 180 is pivoted at one end to hanger rod 155 at 181, its other end sliding along the upper edge of lever 160 when this is moved down from the normal position of Fig. 6 to that of Fig. 7. A stop 182 is welded to the upper edge of lever 160 in such a position that when the lever is pulled down fully (Fig. 7) the end of brace 180 drops behind the stop, holding the lever down and temporarily locking the bulkhead in its lifted position. To lower the bulkhead, lever 160 is depressed slightly below the position shown in Fig. 7 and the end of brace 180 is lifted over stop 182. Then, as lever 160 is allowed to rise, lowering the bulkhead, brace 180 will be returned automatically to its position in Fig. 6. The ring 183 swings freely in a hole 184 near the end of brace 180 and loosely embraces lever 160, allowing sufficient freedom for the above described action, but insuring correct cooperation between brace and lever.

Lever 160 is also automatically releasably locked in its upper (bulkhead lowering) position by a pivoted rod 190 which normally lies across the open front of central column 120 in front of lever 160. This rod is loosely pivoted under a plate 191 which is mounted in any suitable way on an interior side wall of column 120 at approximately the level shown in Figs. 5 and 6. Both ends of rod 190 are bent at right angles to the pivoted section, the end 190 at the front of the bulkhead being long enough to strike the opposite interior wall of column 120 when it is turned to an angle appreciably above the horizontal (see Fig. 5). The end of rod 190 at the back of the bulkhead projects slightly upward from the plane defined by the rest of the rod, and may be cut quite short as indicated at 192 in the figures. The function of this short section is to act as a stop against upward rotation of the rod as a whole, preventing it from assuming a vertical position from which gravity might not return it to the crosswise position of Fig. 5. In the latter position it effectively locks lever 160 in its bulkhead lowering position (Fig. 6). To

75 walls.

raise the bulkhead, lever 190 is simply turned upward with one hand while handle 159 is pulled forward and downward with the other. As soon as lever 160 and brace 180 are out of the way rod 190 may be released and will return to its normal position across the open front of column 120 (Fig. 7). When the bulkhead is again lowered, the upward motion of brace 180 automatically raises rod 190 out of the way. When lever 160 reaches its highest position (Fig. 6) rod 190 drops by gravity into its locking position. Thus whenever the bulkhead is fully lowered the lifting mechanism is automatically locked in this position.

The dimensions of the bulkhead lifting mechanism are so chosen that when the bulkhead is fully lifted it becomes entirely free of the restraints against transverse motion, already described, along its lower edge and at its upper corners. The bulkhead and its hanger rod 155 can therefore readily be rotated about a vertical axis, the hole 93 in trolley block 94 acting as a swivel bearing, and head 157a supporting as a thrust bearing the entire weight of the bulkhead. The bulkhead can also be moved with trolley 90 along track 80, by pulling or pushing upon handle 159 (now in the position shown in Fig. 7) or upon the bulkhead itself.

Also, when the bulkhead is lowered in either of its two operating positions, with lever handle 159 held by locking bar 190 close to the face of the bulkhead (Fig. 6), the dimensions of the apparatus and the setting of the screw adjustment between 175 and 155 in the hanger rod are such as to raise the head 157a of the hanger rod free of carriage 90 and press it firmly against the upper interior surface 83 of channel track 80. The bulkhead is thus positively locked down in either of its lowered positions in engagement with the restraints against transverse motions referred to in the preceding paragraphs; and it cannot be jarred free of them even by violent motion of the car. Yet the release of this lock requires no special motion, but is accomplished automatically when bar 190 is raised and handle 159 operated to lift the bulkhead, as described above.

When the bulkhead is moved outwardly to open the bunker (see position *c* in Fig. 9 and positions *e* and *f* in Fig. 10) it can be lowered if desired till its lower edge rests on the lading floor of the car. However, since it is then higher than when in either of its operating positions *a* and *b*, lever 160 cannot be returned to its position within the bulkhead (Fig. 6) without raising the upper end of hanger rod 155 above the upper web 83 of track 80. To make this possible, a slot such as 84, Fig. 2, can be cut in web 83 at whatever part of the track such motion may be desired.

When the bulkhead is in the lading position against the car end wall, closure of the ice hatches over the bunker space against rain and marauders is normally accomplished by means of a hatch shield slidably mounted just below the car ceiling. Such a hatch shield is shown at 195 in fragmentary plan in Fig. 1, in partial section in Figs. 2 and 5 for example, and in partial elevation in Fig. 4. Hatch shield 195 preferably consists of a flat panel 196 strengthened by the relatively light edge strips 197 along its inner edge and 198 along its ends, and the relatively rigid channel strip 199 along its outer edge. End edge strips 198 are slidably supported by tracks 200 formed of angle iron secured to the car side

According to our invention hatch shield 195 is linked directly to hanger rod 155 by any suitable means, such as the shallow channel member 205. As shown in Figs. 5 and 6, for example, this extends along the transverse center line of the hatch cover and projects beyond its inner edge. A flanged hole 206 in the projecting section of channel 205 (Fig. 6) receives hanger rod 155, so that whenever trolley 90 and the suspended bulkhead are moved along track 80, hatch cover 195 slides correspondingly on its tracks 200. In particular, when the bulkhead is stowed against the car end wall, hatch shield 196 overlies the normal bunker space and is immediately below the hatch openings in the car roof. If, for example, a man jumps through an open hatch onto the hatch shield, the latter will flex downward until channel 205 is supported by clip 158, or, if no such clip is used, until its inner edge 197 is supported centrally by upper channel 140, 141 of the bulkhead. The outer edge of the shield is supported only at its ends on rails 200, but edge reinforcing channel 199 is of sufficiently deep section (Fig. 2) to prevent shield 195 from being easily broken or excessively deformed. Certain aspects of the invention as defined by the following claims (for example those having to do with the bulkhead structure, its carriage and securing it in position) are not necessarily limited to use in an ice bunker, but are useful in any movable partition for a car or the like.

We claim:

1. In a refrigerator car structure, or the like which has a floor, roof and side and end walls, a movable transverse bulkhead, and means for securing the bulkhead in a transverse plane spaced from the end wall in a bunker forming position dividing the car interior into a load compartment and an ice bunker between that compartment and the end wall; the combination of means supporting the bulkhead in the car structure for movement longitudinally between the end wall and the bunker forming position and for longitudinal movement from the bunker forming position into the load compartment, said supporting means incorporating a pivotal mounting for the bulkhead whereby the bulkhead may be swung from a position in a transverse plane into a position out of that plane to afford access to the ice bunker from the load compartment, an ice grate, means for securing one edge of the ice grate on the car end wall, means for supporting the opposite edge of the ice grate on the bulkhead when the latter is in its bunker forming position, and means for locking the bulkhead to the last mentioned supported edge of the ice grate to prevent movement of the bulkhead into the load compartment.

2. In a refrigerator car structure, or the like which has a floor, roof and side and end walls, a movable transverse bulkhead, and means for securing the bulkhead in a transverse plane spaced from the end wall in a bunker forming position dividing the car interior into a load compartment and an ice bunker between that compartment and the end wall; the combination of means supporting the bulkhead in the car structure for movement longitudinally between the end wall and the bunker forming position and for longitudinal movement from the bunker forming position into the load compartment, said supporting means embodying a longitudinal suspension rail associated with the car roof and extending centrally of the car structure from the end wall into the load compartment, bulkhead

suspending means adapted to travel the rail, said suspending means embodying a rail travelling trolley, a suspension element connecting the trolley with the bulkhead at substantially its transverse center, and a swivel structure allowing swinging of the bulkhead about a central vertical axis, all whereby the bulkhead may be moved from its bunker forming position either to a transverse position against the end wall, or to a position in the load compartment in a non-transverse plane to afford access to the bunker space from the load compartment.

3. The combination as defined in claim 2 and also including, an ice grate, means for securing one edge of the ice grate on the car end wall, means for supporting the opposite edge of the ice grate on the bulkhead when the latter is in its bunker forming position, and means for locking the bulkhead to the last mentioned supported edge of the ice grate to prevent movement of the bulkhead into the load compartment, said locking means being releasable by raising the bulkhead-supported edge of the ice grate.

4. The combination as defined in claim 2, and in which the longitudinal suspension rail extends from the bunker forming position of the bulkhead into the load compartment at least a distance substantially equal to the half-width dimension of the bulkhead, so that the bulkhead when moved into the load compartment may be swung about its central vertical axis into a longitudinal plane.

5. The combination as defined in claim 2, and in which the means for securing the bulkhead in bunker forming position embodies elements associated with the car structure and forming recesses into which the bulkhead is lowered, and bulkhead lifting and lowering means associated with the bulkhead suspension element.

6. In a refrigerator car structure, or the like which has a floor, roof and side and end walls, a movable transverse bulkhead, and means for securing the bulkhead in a transverse plane spaced from the end wall in a bunker forming position dividing the car interior into a load compartment and an ice bunker between that compartment and the end wall; the combination of means supporting the bulkhead in the car structure for movement longitudinally between the end wall and the bunker forming position and for longitudinal movement from the bunker forming position into the load compartment, said supporting means incorporating a pivotal mounting for the bulkhead whereby the bulkhead may be swung from a position in a transverse plane into a position out of that plane to afford access to the ice bunker from the load compartment, a movable ice grate for the ice bunker, means for supporting the ice grate at the level of the car floor, and collapsible means for supporting the ice grate independently of the bulkhead at a level above the lower edge of the bulkhead.

7. The combination as defined in claim 2, and in which the car structure has a roof hatch over the bunker space, and including also a hatch closure panel mounted in the car structure for longitudinal movement closely under the roof, said hatch closure being connected to the bulkhead suspension element for longitudinal movement therewith.

8. In a car structure or the like which has a floor, roof and side and end walls, and a transverse bulkhead movable between two or more positions; means for carrying the bulkhead between its several positions and for securing it in

at least one of those positions, said means embodying elements associated with the car structure and forming an upwardly facing securing recess into which the bulkhead may be lowered, longitudinally extending track means having an upwardly facing and a downwardly facing surface, carriage and suspension means for the bulkhead including a suspension element, means for forcibly moving that element vertically with relation to the bulkhead to raise and lower the latter, a trolley element associated with the suspension element and engaging the upwardly facing track surface to support that element and the bulkhead, and a shoulder associated with the suspension element and adapted to move upwardly against the downwardly facing track surface when the suspension element is moved up with relation to the bulkhead.

9. In a car structure or the like which has a floor, roof and side and end walls, and a transverse bulkhead movable between two or more positions; means for carrying the bulkhead between its several positions and for securing it in at least one of those positions, said means embodying elements associated with the car structure and forming an upwardly facing securing recess into which the bulkhead may be lowered, longitudinally extending track means having an upwardly facing and a downwardly facing surface, a trolley riding the upwardly facing track surface, a vertical suspension rod supported by the trolley but upwardly movable relative thereto, a shoulder on the suspension rod adapted to move up against the downwardly facing track surface, and means for forcibly moving the suspension rod vertically with relation to the bulkhead to raise and lower the latter and to force the rod shoulder against the downwardly facing track surface when the bulkhead is lowered into the securing recesses.

10. In a refrigerator car structure or the like which has a floor, roof and side and end walls, a movable transverse bulkhead, and means for securing the bulkhead in a transverse plane spaced from the end wall in a bunker forming position dividing the car interior into a load compartment and an ice bunker between that compartment and the end wall; the improvement which comprises a floor frame including a transversely extending beam engageable by the lower edge of the bulkhead when the latter is in its bunker forming position, the bulkhead and beam having interengaging surfaces which hold the bulkhead against relative movement longitudinally of the car, and transversely spaced thrust transferring struts extending from the beam to the car end wall.

11. In a refrigerator car structure or the like which has a floor, roof and side and end walls, a movable transverse bulkhead adapted to occupy a position in a transverse plane spaced from the end wall in a bunker forming position dividing the car interior into a load compartment and an ice bunker between that compartment and the end wall, and a lading floor for the load compartment spaced above the car floor; a bulkhead supporting and securing beam extending transversely across the car in said transverse plane and adapted to be engaged by the lower edge of the bulkhead, and transversely spaced longitudinally extending struts associated with the beam and supporting it above the level of the car floor at substantially the level of the lading floor, and said struts extending longitudinally from the

beam to bear against the car end wall to transfer thrusts from the beam to that wall.

12. In a refrigerator car structure or the like which has a floor, roof and side and end walls, a movable transverse bulkhead adapted to occupy a position in a transverse plane spaced from the end wall in a bunker forming position dividing the car interior into a load compartment and an ice bunker between that compartment and the end wall, and a lading floor for the load compartment spaced above the car floor; a bulkhead supporting and securing beam extending transversely across the car in said transverse plane and adapted to be engaged by the lower edge of the bulkhead, and transversely spaced longitudinally extending struts associated with the beam and supporting it above the level of the car floor at substantially the level of the lading floor, said struts extending longitudinally from the beam to bear against the car end wall to transfer thrusts from the beam to that wall, an ice grate supporting end wall frame associated with the car end wall, and a grate supporting apron extending across the spaced struts adjacent the bulkhead supporting beam.

13. In a refrigerator car structure or the like which has a floor, roof and side and end walls, a movable transverse bulkhead adapted to occupy a position in a transverse plane spaced from the end wall in a bunker forming position dividing the car interior into a load compartment and an ice bunker between that compartment and the end wall, the bulkhead adapted to be moved to a position against the car end wall, and a lading floor for the load compartment spaced above the car floor; a bulkhead supporting and securing beam extending transversely across the car in said transverse plane and adapted to be engaged by the lower edge of the bulkhead, spaced means supporting the beam above the car floor so that the air passage existing under the lading floor is continued under the beam into the ice bunker, a foraminous ice grate extending substantially from the bulkhead supporting beam to the car end wall, means for supporting the grate at substantially the level of the lading floor, said bulkhead being cellular with a vertical air passage therethrough leading from its lower edge to its upper portion and thereby establishing a vertical air passage adjacent the car end wall when the bulkhead is against that wall and over the foraminous ice grate, and the bulkhead supporting beam being imperforate so as to close off the vertical passage through the bulkhead when the latter is in its position over the beam.

14. In a refrigerator car structure or the like which has a floor, roof, and side and end walls, a movable transverse bulkhead adapted to occupy a position in a transverse plane spaced from the end wall in a bunker forming position dividing the car interior into a load compartment and an ice bunker between that compartment and the end wall, and an ice grate in the bunker; the combination of means for supporting the ice grate comprising, an end wall frame associated with the car end wall, said frame embodying horizontally spaced vertical channels and vertically spaced horizontal channels, grate securing elements connected with the grate and engaging the vertical channels to be vertically movable therein, a hook formation on the grate adapted to engage any of the several horizontal channels for support of one edge of the grate, and supporting means independent of the bulkhead for supporting the opposite edge of the grate.

19

15. In a refrigerator car structure or the like which has a floor, roof and side and end walls, a movable transverse bulkhead adapted to occupy a position in a transverse plane spaced from the end wall in a bunker forming position dividing the car interior into a load compartment and an ice bunker between that compartment and the end wall, and an ice grate in the bunker; the combination of means for supporting the ice grate comprising, an end wall frame associated with the car end wall, said frame embodying horizontally spaced vertical channels and vertically spaced horizontal channels, grate securing elements connected with the grate and engaging the vertical channels to be vertically movable therein, a hook formation on the grate adapted to engage any of the several horizontal channels for support of one edge of the grate, and supporting means independent of the bulkhead for supporting the opposite edge of the grate, said last mentioned supporting means embodying a floor frame, means for supporting said edge of the grate directly on the floor frame, and a grate supporting frame pivoted to the floor frame and adapted to be swung either to a position in a substantially horizontal plane against the floor frame or to an upright position to form a support for said edge of the grate at a level above the floor frame.

16. In a car structure or the like which has a floor, roof and side and end walls, a movable bulkhead structure comprising upper and lower horizontal beams adapted to extend across the car interior substantially from side to side, a plurality of hollow cellular wall forming units extending vertically between and secured at their tops and bottoms to the upper and lower beams, and means for securing the bulkhead in a transverse plane across the car interior comprising securing units associated with the car structure and engaging the bulkhead beams.

17. The combination as defined in claim 16 and in which each of the wall forming units comprises a hollow box structure including top, bottom and side walls of outwardly facing channel formation, vertically spaced interior stiffeners extending between the side walls, and front and rear face walls of corrugated metal secured to the top, bottom and side walls, the upper and lower bulkhead beams being secured within the outwardly facing channels of the top and bottom walls of the several units.

18. In a car structure or the like which has a floor, roof and side and end walls, a movable bulkhead structure comprising upper and lower horizontal beams adapted to extend across the car interior substantially from side to side, a central hollow box-like column extending vertically between and secured at its top and bottom to the upper and lower beams, at least one hollow box-like wall forming unit at each side of the central column extending vertically between and secured at top and bottom to the upper and lower beams, carriage and support means for the bulkhead embodying a suspension and lifting means housed

20

within the hollow central column, and means for securing the bulkhead in a transverse plane across the car interior comprising securing units associated with the car structure and presenting upwardly facing recesses adapted to receive the lower beam and to receive the end portions of the upper beam.

19. A bulkhead structure for a car or the like, comprising upper and lower horizontal beams, a plurality of hollow cellular wall forming units extending vertically between and secured at their tops and bottoms to the upper and lower beams, each of the wall forming units comprising a hollow box-like structure including top, bottom, and side walls of outwardly facing channel formation, vertically spaced interior stiffeners extending between the side walls, and front and rear face walls of corrugated metal secured to the top, bottom and side walls, the upper and lower bulkhead beams being secured within the outwardly facing channels of the top and bottom walls of the several units.

20. In a refrigerator car structure, or the like which has a floor, roof and side and end walls, a movable transverse bulkhead, and means for securing the bulkhead in a transverse plane spaced from the end wall in a bunker forming position dividing the car interior into a load compartment and an ice bunker between that compartment and the end wall; the combination of means supporting the bulkhead in the car structure for movement from the bunker forming position into the load compartment, said supporting means incorporating a swinging mounting for the bulkhead whereby the bulkhead may be swung from a position in a transverse plane into a position out of that plane to afford access to the ice bunker from the load compartment, an ice grate, means independent of the bulkhead for supporting the grate at the car floor level, and other means independent of the bulkhead for supporting the ice grate at an icing level above the car floor level.

21. The combination defined in claim 20 and in which the two grate supporting means include grate supporting formations associated with the end wall and by which one edge of the grate is adapted to be supported at either level, a floor frame having means for supporting the opposite edge of the grate at the lower level, and grate supporting frame foldingly mounted on the floor frame and adapted to be moved to a position to support said opposite grate edge at the higher level.
